CLAIM

The ornamental design for an outdoor storage box, as shown and described.

DESCRIPTION

FIG. 1 is a perspective view of an outdoor storage box showing my new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof;

FIG. 8 is an enlarged view of the encircled area 8 of FIG. 1;

FIG. 9 is an enlarged view of the encircled area 9 of FIG. 2; and,

FIG. 10 is an enlarged view of the encircled area 10 of FIG. 7.

The broken lines shown in the figures depict portions of the outdoor storage box that do not form part of the claimed design. In FIGS. 1, 2 and 7-10, the broken lines depict the enlarged view boundaries that do not form part of the claimed design.

1 Claim, 10 Drawing Sheets
